UNITED STATES PATENT OFFICE.

ANTON SOLMAN AND ALBIN SLIWINSKI, OF PITTSBURGH, PENNSYLVANIA.

TRIGGER MECHANISM FOR AUTOMATIC FIREARMS AND PISTOL-SWORDS.

1,221,616.

Specification of Letters Patent.

Patented Apr. 3, 1917.

Application filed September 7, 1916. Serial No. 118,841.

To all whom it may concern:

Be it known that we, ANTON SOLMAN and ALBIN SLIWINSKI, subjects of the Emperor of Austria, residing at Pittsburgh, in the 5 county of Allegheny and State of Pennsylvania, have invented certain new and useful Improvements in Trigger Mechanisms for Automatic Firearms and Pistol-Swords, of which the following is a specification.

10 In firearms of the automatic type, it is sometimes necessary to locate the trigger at a distance from the tripping mechanism for the firing pin and the primary object of the present invention is the provision of suitable means for connecting the trip mechanism with the distantly positioned trigger in such structures for example as that set forth in our copending application for a pistol-sword.

20 A particular object of the device is the provision in a pistol-sword of a trigger mechanism and connector carried by the sword hilt operatively connected with the trip mechanism for the firing pin arranged 25 within the pistol, the trigger being conveniently positioned for operation while grasping the hilt and arranged within the hand guard of the latter.

30 A further object of the device is the provision of a sword-pistol having the cartridge magazine casing forming an integral part of the hand guard of the hilt and with trigger mechanism for the pistol operable within the hand guard rearwardly of said casing 35 and adjacent the handle portion of the hilt and gun combined.

40 In the drawing forming a part of this application and in which like reference characters designate corresponding parts throughout the several views:—

Figure 1 is a side elevation of a pistol-sword provided with the present device, parts being broken away.

45 Fig. 2 is a top plan view thereof with the pistol barrel and slide removed, the sword blade being broken away.

Fig. 3 is a perspective view of the trip block for the firing mechanism.

50 Fig. 4 is a perspective view of the buffer member employed with the trip block.

Fig. 5 is a perspective view of the pusher block employed with the trip block.

Fig. 6 is a perspective view of a rocker forming a portion of the trigger mechanism.

55 Fig. 7 is a perspective view of the extension rod and connecting pin employed.

Fig. 8 is a removable section of the extension rod.

Fig. 9 is a perspective view of a guard or cover plate for the rocker and trigger, and 60

Fig. 10 is a side view of a portion of the firing mechanism assembled and removed.

Referring more in detail to the drawing, it will be noted that the general construction of the device consists of a sword blade 65 10 having a hilt 11 provided with a hand guard 12 and a handle 13, the latter also serving as a butt of the automatic pistol formed with the sword and having a barrel 14 and a casing 15 adapted for the reception of the cartridge magazine 16 of substantially the usual form, it being noted that the sword and hilt together with the casing 15 are integrally formed with the casing 17 of the pistol, the trigger mechanism being 70 75 adapted for operating the pistol when grasping the handle of the pistol-sword.

A firing mechanism is provided in the casing 17 which is of the usual form employed with automatic pistols of the Searle 80 type as shown in Patent #936,639 dated October 12, 1909, which includes a sear connector 18 with a plunger or latch 19, the latter having a shaft 20 with an encircling spring 21 thereon and arranged within the body 22 of the said connector 18, a head 23 being carried by the said shaft rearwardly of the body 22 with the adjacent reduced cylindrical portion 24 of the head slidably arranged within a socket 25 in the connector body 22. A trigger block 26 has a side rib 27 arranged beneath a ledge 28 of the pistol casting 17 within the chamber 29 thereof, the said trigger block having a recess 30 at a point therein opposite the rib 27, a projecting stud 31 of the connector 18 being 85 90 95 journaled within the recess 30 when the device is assembled, and at which time the connector body 22 is positioned within the cut-away side portion 32 of the trigger block 26. By this arrangement it will be seen that the connector 18 is pivotally carried by the trigger block 26 allowing the free operation of the actuating finger 33 of the connector as well as the usual operation of the latch head 23, which latter has the usual side lug 34 positioned adjacent the stop 35 of the connector body 22. The trigger block 26 being longitudinally slidably arranged, carries the connector 18 therewith, 100 105 110 at each operative shifting of the trigger block, all of which is in the usual manner

as shown in the said patent to Searle, #936,639, the relative position of the actuating connector finger 33 and the sear 60 with the firing pin 61 of the lock mechanism 5 being indicated in Fig. 10 of the drawing.

The present invention provides an extension member or bar which includes a rod 37 longitudinally slideable through a journaling passage 38 upon an enlargement or 10 side projection 39 of the casting 17, the said rod having a head 40 arranged forwardly of the said enlargement while an encircling spring 41 is carried by the rod 37 within the enlarged forward end 42 of 15 the passage 38. A screw 43 is connected between the extension rod head 40 and the base 44 of the trigger block 26, the said screw extending through a slot 45 in the bottom of the chamber 29.

20 An extension 46 of greater diameter than the rod 37 is screw-threaded upon the rear end of the rod 37 rearwardly of the enlargement 39 maintaining the rod in its longitudinally shiftable position within the passage 38. A rocker 47 is pivoted as at 48 to the pistol casting 17 rearwardly of the enlargement 39 and has a reduced end 49 freely engaging within a longitudinal slot 50 of the extension 46. A trigger 51 is 25 pivoted to the casting 17 as at 52 and has a curved arm 53 frictionally engaging the rounded base portion 54 of the rocker 47 whereby the free end 55 of the trigger when pulled rearwardly will tilt the rocker 47 30 forcing its end 49 rearwardly carrying the extension member and its extension in a corresponding direction against the action of the spring 41. Such movements force the trigger block 26 rearwardly carrying the 35 pivoted connector 18 therewith for operating the automatic pistol mechanism for firing the same. The spring 41 automatically returns the trigger block 26 and extension member mechanism forwardly to 40 their normal positions upon releasing the pressure upon the trigger 51.

It will be understood that by the arrangement described the combined handle 13 for the sword and pistol may be grasped by the 50 hand of the operator for readily employing

the blade 10 as a sword or saber while the trigger 55 is arranged for convenient use within the hand-guard 12 to be readily pulled by the finger whenever desiring to fire the automatic pistol. A guard or cover plate 56 is arranged over the rocker 47 and the upper end of the trigger 51 when the device is assembled, the said plate being illustrated in position by dotted lines in Fig. 1, it being understood that any desirable form of cover or hand grip is positionable thereover which also overlies the extension member and rocker portions positioned rearwardly of the enlargement 39, the head 40 of the extension member being exposed 60 forwardly of the said enlargement. 65

What we claim as new is:

1. A pistol sword including a sword and hilt integrally formed, a cradle formed integral with the sword and hilt, an automatic pistol supported in said cradle, a trigger pivoted to the hilt, and connections between the trigger and pistol firing mechanism. 70

2. A pistol sword including a sword element comprising an integrally formed hilt, a cartridge casing, and a cradle superposed upon said cartridge casing, an automatic pistol mounted in the cradle, and trigger mechanism for the pistol carried by the hilt. 75

3. A pistol sword including a sword element having a hilt, and a cradle carried thereby, an automatic pistol mounted in the cradle, a trigger pivoted to the hilt, and a tensioned longitudinally shiftable rod connecting the trigger and the pistol firing 80 mechanism. 85

4. A pistol sword including a sword element having a hilt, a cradle carried thereby, an automatic pistol mounted in the cradle, a trigger pivoted to the hilt, a tensioned longitudinally shiftable rod, means connecting the forward end of the rod to the firing mechanism of the pistol, and means connecting the rear end of the rod to the trigger. 90 95

In testimony whereof we affix our signatures.

ANTON SOLMAN.
ALBIN SLIWINSKI.
